(57) **CLAIM**

The ornamental design for an alarm device, as shown and described.

DESCRIPTION

FIG. 1 is a front, right, bottom perspective view of a first embodiment of an alarm device;

FIG. 2 is a back, right, top perspective view thereof;

FIG. 3 is a bottom plan view thereof;

FIG. 4 is a top plan view thereof;

FIG. 5 is a right-side elevation view thereof;

FIG. 6 is a left-side elevation view thereof;

FIG. 7 is a front elevation view thereof;

FIG. 8 is a back elevation view thereof;

FIG. 9 is a front, right, bottom perspective view of a second embodiment of an alarm device. The second embodiment shows the alarm device of FIGS. 1-8 as graphical renderings;

FIG. 10 is a back, right, top perspective view thereof;

FIG. 11 is a bottom plan view thereof;

FIG. 12 is a top plan view thereof;

FIG. 13 is a right-side elevation view thereof;

FIG. 14 is a left-side elevation view thereof;

FIG. 15 is a front elevation view thereof; and,

FIG. 16 is a back elevation view thereof.

The broken lines depict portions of the alarm device that form no part of the claimed design.
